UNITED STATES PATENT OFFICE.

ELISHA F. BEAVERSTOCK, OF HOLYOKE, MASSACHUSETTS, ASSIGNOR TO DEAPNEE CORPORATION, OF HOPEDALE, MASSACHUSETTS, A CORPORATION OF MAINE.

WEFT CLAMPING AND PARTING MECHANISM FOR LOOMS.

1,265,590.

Specification of Letters Patent.

Patented May 7, 1918.

Application filed September 25, 1917. Serial No. 193,083.

To all whom it may concern:

Be it known that I, ELISHA F. BEAVERSTOCK, a citizen of the United States, residing at Holyoke, county of Hampden, State of Massachusetts, have invented an Improvement in Weft Clamping and Parting Mechanism for Looms, of which the following description, in connection with the accompanying drawing, is a specification, like characters on the drawing representing like parts.

This invention relates to mechanism for clamping and parting the weft of the abandoned filling carrier in weft replenishing looms.

In looms such as the automatic weft replenishing loom of the Northrop type it is necessary when weft replenishment takes place to part or sever the weft adjacent the edge of the cloth and to provide means for preventing the trailing end extending to the abandoned filling carrier from being caught by the fresh filling carrier or the mechanism of the loom and thrown or whipped back into the shed where it would cause an imperfection. Various mechanisms have been provided for this purpose.

The present invention provides mechanism in which the end extending from the edge of the cloth to the filling carrier is severed or parted at two points, first, adjacent the filling carrier itself, and, second, adjacent the edge of the cloth, and wherein the severed section is seized by clamping means and carried forward out of the way and dropped at a point where there will be no danger of its being caught and thrown into the shed.

The present invention has for its object to provide a combination of elements for securing this result, also to provide a simple and efficient mechanism for severing or parting the weft adjacent the filling carrier, and also a simple and efficient mechanism for clamping the weft and securing its removal and discharge from the loom.

These and other features of the invention will appear more fully from the accompanying description and drawings and will be particularly pointed out in the claims.

The invention is illustrated in connection with an automatic weft replenishing loom of the well known Northrop type, but it will be obvious that it may be embodied in any

type of loom wherein the results which are accomplished by it are desirable. 55

In the drawings,

Figure 1 is an elevation partly in vertical cross section looking from the center toward the inside of the transfer end of a loom of the Northrop type with only those parts shown which are necessary to a disclosure of the invention;

Fig. 2 is a top plan view partly in horizontal cross section of a portion of the transfer end of the loom showing the same form 65 of the invention as in Fig. 1 in position;

Fig. 3 is a side elevation partly in vertical cross section taken through the shuttle, shuttle box and lay with a preferred form 70 of the parting means adjacent the filling carrier in place;

Fig. 4 is a longitudinal vertical cross section of the device for operating the parting means shown in Fig. 3;

Fig. 5 is a view principally in horizontal 75 cross section of the construction shown in Fig. 3;

Fig. 6 is a cross sectional view taken on the line A—A of Fig. 4;

Fig. 7 is a side elevation of the clamping 80 mechanism shown as supported on the upper end of a usual shuttle feeler;

Fig. 8 is a view similar to Fig. 7 showing the parts in a different position.

Fig. 9 is a top plan view of the construction shown in Fig. 7;

Fig. 10 is a view in side elevation taken from the opposite side of Fig. 7;

Fig. 11 is a view in vertical cross section taken on the line B—B of Fig. 7. 90

The invention is illustrated for convenience of disclosure in connection with the well known type of Northrop automatic weft replenishing loom, but as the particular construction of loom forms no part of 95 the invention in its broader aspects, it is unnecessary to illustrate or describe the loom in detail.

It will be sufficient to note that the loom comprises a frame 1, the sides of which are 100 connected by the breast beam 2, the lay 3 supported on the lay sword 4 and carrying at each end shuttle boxes. The shuttle box 5 at the transfer end is shown with the shuttle 6, and its substantially exhausted filling 105 carrier 7, boxed therein. The transfer mech-

anism is shown as including a hopper 8 supported from the loom frame 1 and carrying a supply of fresh filling carriers 9. Upon the call for filling replenishment the usual 5 starter rod or shaft 10 is rotated to raise the arm 11 against the tension of the spring 12 and allow the shuttle feeler 13, pivoted at 14, to swing rearwardly and simultaneously elevate the dog 15 pivoted on the depending 10 shorter arm 16 of the transferrer 17 into the path of the bunter 18 carried by the lay. As the lay beats up, if the shuttle feeler indicates that the shuttle is properly boxed, the bunter 18 contacting with the dog 15 15 will depress the transfferer 17 which will force a fresh filling carrier 9 out of the hopper 8 into the shuttle therebeneath, forcing out and discharging the exhausted filling carrier 7, all in a manner well known and 20 familiar to those skilled in this art.

The filling extending from the abandoned filling carrier 7 through the eye of the shuttle to the edge 19 of the cloth must be taken care of and removed from liability of being thrown into the shed or woven into the cloth.

In this invention mechanism is provided for severing this end at two points, first, at a point adjacent the shuttle, and not far 30 from the eye thereof so that but a short end is left to be drawn out of the eye, and, next, at a point close to the edge 19 of the cloth.

At the latter point any well known form of temple thread cutter 20 may be employed 35 for severing or parting the weft. At the former point mechanism is provided which is illustrated in detail in Figs. 3 to 6 inclusive.

The shuttle box 5 at the transfer end of 40 the loom is provided at a point intermediate its ends and in its front wall or face with an aperture 21, and a corresponding aperture 22 is formed in the side wall of the shuttle so that when the shuttle is boxed 45 these apertures are in alinement. A cutter support shown as an L-shaped bracket 23 is supported and carried by the lay opposite the shuttle box, being preferably mounted directly on the front face of the front wall of 50 the shuttle box 5 by suitable means such as the screw 24. This support is provided with a pair of scissor-like cutting blades movably mounted thereon and so located that when moved they enter the alined apertures 55 21 and 22 and then close, thus severing the filling. In the construction illustrated a slide bar 25 is mounted to slide transversely of the shuttle box on the face of the forwardly projecting arm 26 of the cutter support. 60 This slide bar is longitudinally slotted to receive and be guided by a pair of screws 27 and 28 threaded into the arm 26 and locked in place by lock nuts 29 and 30. A pin 31 is threaded into the rearward end of the 65 slide 25 and projects at both sides thereof,

a slot 32 being provided in the arm 26 for that purpose. A helical contracting spring 33 is secured at one end to the projecting portion of the pin 31 and at the opposite end to a projecting portion of the screw 28 so 70 that the slide 25 is held normally retracted as shown in Figs. 3 and 4. The scissor-like cutting blades 34 and 35 are pivoted on the pin 31 at the face of the slide bar 25 and are held in frictional cutting engagement by a 75 helical spring 36 mounted on the pin 31 between the blades and an adjusting nut 37 on the end of the pin. The forward ends of the blades 34 and 35 are provided with cam-shaped slots 38 and 39, respectively, which fit over 80 the pin 27 so that as the blades are moved forwardly and rearwardly with the slide bar 25 they are opened and closed. A suitable casing 40 is held in position to cover and protect the blades by being secured against 85 shouldered portions of the pins 27 and 28 by the nuts 41.

The operation of this cutting instrumentality is secured at the proper time through the transfferer. The lower arm 16 of the 90 transfferer has pivotally mounted at the lower end thereof the usual dog 15. The pivot pin 42 in this case is locked to the dog 15 by a set screw 43 and is conveniently extended at one side and provided with an 95 integral head portion 44, as shown in Fig. 6. This head portion is bored transversely at 45 to receive a guide pin 46, an enlarged section 47 of which is threaded into one end of the bore 45 and locked in longitudinal adjustment by the nut 48. A sliding dog shown as a plate 49 provided with lateral flanges 50, 51 and 52 is mounted on the head 44 and guide pin 46. This is secured by providing the plate 49 with beveled edges 105 and fitting it in a correspondingly shaped slot in the face of the head 44 and providing the flanges 51 and 52 with apertures fitting over the guide pin 46. A helical spring 53 surrounds the pin 46 between the threaded 110 section 47 and the flange 51 and thus serves normally to project the sliding dog rearwardly until the flange 52 contacts with the end of the threaded section 47. The position to which the sliding dog is thus rearwardly projected is adjustable by varying the longitudinal position of the guide pin 46 in the head 44 by means of the threaded section 47 and lock nut 48.

The operation of this parting or severing 12 mechanism will now be apparent. The sliding dog mechanism shown in Figs. 4 and 6 is mounted on the dog 15 in line with the slide bar 25 and in such position that during the normal operation of the loom when the 12 lay beats up the slide bar 25 will come opposite the head 44 and enter if necessary the slotted portion 54 thereof. Thus, during the normal operation of the loom the slide 25 and consequently the mechanism will not 13

be actuated. Upon the call for filling replenishment the dog 15 will be elevated in the usual manner and through the medium of the pivot pin 42 will carry with it the 5 sliding dog mechanism, swinging it into such position that the outer flange 50 of the sliding dog is in the path of the slide bar 25. As the lay now beats up the end of the slide bar 25 engages the flange 50 and is forced 10 thereby rearwardly against the tension of the spring 33 causing the cutting blades to enter the aperture in the shuttle and sever the end of the weft extending from the eye of the shuttle toward the cloth. By adjusting 15 the guide pin 46 longitudinally the proper movement and operation of the cutting blades may be insured. As the lay retracts the spring 33 restores the cutting blades to normal retracted position and, 20 transfer having taken place, the sliding dog with its flange 50 drops with the dog 15 and is carried out of the path of the slide bar 25.

The severed end extending from adjacent 25 the shuttle eye, or from the point at which it is severed by the cutting mechanism just described, to the edge of the cloth is taken care of, first, by bringing it into the field of operation of the temple thread cutter 20 by which it is again severed, this time close 30 to the edge of the cloth and, then, by carrying it forwardly and dropping or discharging it at such a point that it will not be liable to be caught and thrown or carried into the shed. For all these purposes this invention 35 provides a mechanism, a preferred form of which is illustrated in detail in Figs. 7 to 11 inclusive of the drawing.

This mechanism seizes and clamps the weft preferably at a point adjacent the nose 40 of the boxed shuttle and carries the weft forwardly bringing it into the path of the temple thread cutter and then carries and holds the weft end, now severed and free, to 45 and in a position where it is dropped and discharged from the loom.

This mechanism may be carried by any suitable movable support but for convenience the usual shuttle feeler 13 is utilized. This shuttle feeler upon the call for filling 50 replenishment swings rearwardly past the nose of the boxed shuttle feeling to ascertain if the shuttle is properly boxed and acting if the shuttle is not properly boxed to prevent transfer taking place all in a manner well known and familiar to those skilled 55 in this art.

In the present invention the cutter support, in this case the shuttle feeler 13, is provided at its end with an extended or 60 elongated slot 55 preferably somewhat downwardly curved as indicated so that as the support moves rearwardly it will straddle the weft end and the weft end will pass well into the slot.

65 The clamping mechanism which is carried

by the support comprises essentially a fixed clamping member, that is, a member fixed with relation to the support, a movable and preferably pivoted clamping member mounted on the support, and coöperating 70 with the fixed clamping member to grasp and clamp the weft lying in the slot 55, and a pusher sliding on the side of the fixed clamping member opposite to that side on which the movable clamping member operates, and acting to push the end of the weft extending through the slot 55 out from the slot so that it will hang over the same side of the fixed clamping member as the other end hangs and thus insuring that the severed 80 weft section may be easily and readily discharged from the clamping mechanism when the movable clamping member opens.

The fixed clamping member in the particular form herein illustrated is shown as 85 comprising two parts, namely, a main section and an auxiliary arm. The main section 56 is shown as a plate corresponding in somewhat general shape to the rearward end of the support or shuttle feeler 13 and slotted 90 at its rearward end opposite the slot 55. The auxiliary arm 57 is shown as a thin, flat metal plate lying between the plate 56 and the support 13 and at its rearward end bent laterally and forwardly and having the 95 shape illustrated. These parts are held in place in fixed relation with respect to the support 13 by the studs 58 and 59 passing therethrough and threaded into the support 100 13.

The movable clamping member is shown as a blade-like member 60 having a hook-shaped rearward end 61 and a forwardly depending tail 62. This movable member is pivotally mounted on the stud 63 threaded 105 into the support 13. A helical spring 64 surrounds the outer end of the stud 63 and is seated against the support 13 and the inner face of the movable clamping member 60. It will thus be seen that by screwing in the 110 stud 63 the spring 64 is compressed and the movable cutting blade brought yieldingly and accurately against the fixed blade to insure the proper frictional engagement therewith. When in proper adjustment the 115 stud 63 is locked in place by the screw 65 threaded transversely in the support 13 and abutting the stud. The movable clamping member is yieldingly locked in its open and closed positions by a locking slide mounted 120 thereon. This slide 66 is provided with a heart shaped opening and is mounted on the face of the pivoted clamping member and slotted to engage and slide over a projection 67 and a stud 68 carried by the pivoted 125 clamping member. This locking slide is yieldingly projected rearwardly by a spring 69 secured at 70 to the clamping member and abutting at its ends the tail 62 and the slide 66. The heart shaped opening co- 130

4
operates with the extended end of the stud 59. Thus it will be seen that the pivoted clamping member is yieldingly locked in its extreme positions of movement, that is, in its open and closed positions.

The pusher is shown as a slide bar 71 provided with a longitudinal slot 72 fitting over the studs 58, 59 and 63. This pusher is for convenience mounted in a recess in the inner 10 face of the plate 56. The forward end of the pusher is upturned at 73 and pointed or beveled to engage beneath a spring catch 74 secured to a fixed portion of the loom such as the breast beam 2. This serves as a 15 means to control the movement of the pusher.

Any convenient means may be employed for causing the operation of the movable or pivoted clamping member. When, as in the 20 preferred form illustrated, the clamping mechanism is carried by the shuttle feeler, a transverse pin 75 projecting from the pivoted clamping member 60 may coöperate with a switch cam 76 on the upwardly projecting bracket arm 77, in a manner familiar in this type of construction. Upon the rearward movement of the shuttle feeler this construction operates to swing the clamping member to open position and upon 30 the beat up the lay contacting with the tail 62 acts to swing the pivoted clamping member to closed position.

The operation of this clamping mechanism herein illustrated as a preferred embodiment of this feature of the invention 35 will now be readily understood. The parts normally occupy the position indicated in Fig. 1, the support being in forward position, the tail of the pusher 73 resting against the breast beam and caught beneath the 40 spring 74 holding the pusher projected, the pivoted clamping member being swung downwardly to closed position. Upon the call for filling replenishment the support 45 13 swings rearwardly. As it swings the pusher 71 remains stationary until it is retracted to the limit of its movement when the tail 73 rides from beneath the spring 74 which yields for that purpose, and the pivoted clamping member is swung to open position by engagement of the pin 75 with the switch cam 76. As the support reaches its rearward position the lay beating up causes 50 the weft extending from the shuttle to enter the slot 55 and as this slot is elongated the weft is carried well in between the clamping member. As the lay continues the beat up the weft is severed by the mechanism already described intermediate the ends of the 55 shuttle and the lay striking the tail 62 swings the pivoted clamping member to closed position, thus pinching or clamping the weft between the two clamping members. The severed end of the weft now 60 hangs at the transfer side of the support 13

and clamping mechanism while the other end extends to the fell of the cloth. As the beat up continues the support 13 swinging forwardly carries the weft end into engagement with the temple thread cutter 20 where 70 it is severed in the usual manner. As the beating up movement continues the tail 73 of the pusher rides beneath the spring 74 and comes into contact with the breast beam 2 and is thereby projected so that the parts 75 arrive at the position illustrated in Fig. 8. As the pusher is thus projected it pushes the end of the weft first severed out of the slot 55 and over onto the same side of the fixed clamping member as is occupied by 80 the end of the weft last severed so that both ends of the severed section of weft now hang over the same side of the fixed clamping member or in this case over the same side of the auxiliary arm 57, the weft section remaining held pinched or clamped between the clamping members, all as illustrated in 85 Fig. 8. The parts are now again in the position illustrated in Fig. 1. The weaving operation now continues as usual. Upon the 90 next call for filling replenishment the operation described is repeated and as the pivoted clamping member swings to open position the severed section of weft hanging over the same side of the fixed clamping 95 member is free and drops off. If for any reason it should catch and not drop off it is promptly brushed off by the lay upon the beat up. In any case this severed weft section drops or is brushed off at a point where 100 it cannot be caught and whipped or carried back into the shed to cause an imperfection.

Having fully described my invention, what I claim as new and desire to secure by Letters Patent is:

105

1. In a weft replenishing loom a support movable toward and from the lay and provided with a long weft receiving slot extending into and transversely of its end, a fixed clamping member secured to the 110 side of said support beneath said slot, a pivoted clamping member pivoted on said support and swinging from an open position above said slot into a coöperative clamping relation with said fixed clamping member, 115 a pusher slidably mounted between said support and said fixed clamping member and acting when projected to push the end of a severed weft out of said slot and over the same side of the fixed clamping member as 120 occupied by the other end of said weft.

2. In a weft replenishing loom, a support movable toward and from the lay and provided with a long weft receiving slot extending into and transversely of its end, a 125 fixed clamping member secured to the side of said support beneath said slot, a pivoted clamping member pivoted on said support and swinging from an open position above said slot into a coöperative clamping rela- 130

- tion with said fixed clamping member, a pusher slidably mounted between said support and said fixed clamping member, means to sever the weft at each side of said support, and means acting when replenishment takes place to cause the support to move toward the lay and receive the weft in said slot and between the clamping members, to cause the pivoted clamping member to swing down into coöperation with a clamping member and clamp the weft, to cause the pusher to move rearwardly after severance at each side of said support has taken place and push the end of the slot into the support, thus leaving both ends hanging over the fixed clamping member at the same side thereof, and then to elevate and thus open the pivoted clamping member freeing the weft and permitting it to drop off or be pushed off on a succeeding beat up of the lay.
3. In a weft replenishing loom, a support movable toward and from the lay and provided with a long weft receiving slot extending into and transversely of its end, coöoperating clamping members secured to the side of said support opposite said slot, a pusher slidably mounted between the said support and said clamping members and acting when projected to push a severed weft end held by the clamping members out of said slot so that both ends of the weft will hang over the same side of one of the clamping members and thus be free when the clamping members are opened.
4. In a weft replenishing loom the combination of elements set forth in claim 3 together with means to sever the weft of an abandoned filling carrier at each side of said support.
5. In a weft replenishing loom the combination of elements set forth in claim 3 together with means carried by a fixed part of the loom for effecting the operation of the pusher upon the movement of the said support.
6. In a weft replenishing loom the combination of elements set forth in claim 3 together with means on the loom frame for arresting the forward movement of the pusher as it is carried forward by said support and thus causing its said projection, and a yielding catch for engaging and holding the said pusher during the first part of the rearward movement of the said support.
7. A weft clamping mechanism for weft replenishing looms comprising a movable support slotted longitudinally to receive the weft, a fixed clamping member secured to one side of said support beneath said slot, 60 a movable clamping member mounted at the opposite side of said fixed member and coöoperating therewith to clamp the weft, a pusher slidably mounted between said support and said fixed clamping member and 65 acting when projected after the closing of the clamp to push the weft out of said slot and thus leave the weft held by the clamp with both ends hanging down over the same side of the fixed clamping member whereby 70 upon the opening of the clamp the weft may drop or be readily pushed off.
8. A weft replenishing loom comprising means carried by the lay intermediate the ends of the shuttle when boxed at the transfer end of the loom for severing the weft extending from the shuttle to the cloth, means for severing the weft adjacent the cloth, means for clamping the weft between the said points of severance and carrying 80 it well forward, and means acting after severance to push that end of the weft extending toward the shuttle over onto the same side of the clamping means as the other end so that upon the release of the 85 clamping means the severed weft is free to drop off.
9. In a weft replenishing loom means mounted on the lay for severing the filling extending from the shuttle eye to the cloth, 90 a transerrer, a pivot pin extending laterally from said transerrer, a dog mounted on and slideable transversely of said pivot pin, and means operative on the call for filling replenishment to turn said pivot pin 95 and bring said dog into position to effect the actuation of the severing means upon the movement of the transerrer.
10. In a weft replenishing loom the combination of elements set forth in claim 9 100 together with means for adjusting the rearward limit of the sliding movement of said sliding dog.
11. In a weft replenishing loom the combination of elements set forth in claim 9 105 wherein the yielding sliding movements of said sliding dog is secured by providing said pivot pin with a guide pin extending transversely thereof and transversely adjustable therein, by mounting the said sliding dog on said guide pin, and mounting a helical compression spring between a rearward portion of said sliding dog and a shoulder on said guide pin.

In testimony whereof, I have signed my name to this specification.

ELISHA F. BEAVERSTOCK.
